TELESCOPIC FIREARM

George William Patchett, Chigwell, England

Application June 19, 1944, Serial No. 540,928
In Great Britain March 13, 1944

16 Claims. (Cl. 42—72)

1

This invention relates to improvements in firearms and has for its object the manufacture of a weapon carrying a butt and bayonet and wherein its overall length when required can be greatly reduced. The arrangement proposed becomes possible by having the butt and bayonet fold and by forming the supporting members of the gun mechanism as tubular entities, one of which can telescope within the other. The gain in space achieved in such arrangement is of a high order, since in one form of the device suitable for modern warfare the extended length of the firearm and accessories is 33 inches long, whilst in its telescoped and folded condition the overall length is under 13 inches.

A further object of the invention is to maintain locked rigidity and alignment when the firearm is in its operative or extended condition, as well as to lock the interengaging parts when in its folded condition.

A further object is to provide means for an immediate release at will of the firearm from its telescoped state and have same in a condition for use, a recoil spring being inter alia employed for such purpose.

The invention consists in a new or improved telescopic firearm having in combination two main tubular intertelescopic members of differing diameters and of completely circular cross section arranged coaxially, said tubular members carrying or supporting the entire operative components of the firearm, said members being capable of intentional release and of relative axial movement to telescope and be interlocked in either condition by a sear operatively conditioned by a fire selection lever. Release of said telescoped members is achieved by the manual movement of said fire selection member and extension to an operative condition under resilient means, said telescopic members being temporarily held in said extended position by the bolt recoil spring, and then interlocked by insertion of ammunition magazine.

The said tubular members comprise a main or outer member carrying the trigger gear, hand stock and the barrel; and an inner tubular member carrying a support for the barrel breech and the bolt with associated parts including the bolt recoil spring which is employed to resist intentional telescopic movement, and also tending to automatically extend the weapon after release of the locking device.

The invention is further characterised by the fitting of a folding butt and bayonet, said butt being of a skeleton type, both said parts folding

2

within the compass of longitudinal axial length of the firearm in a telescoped condition, and being secured and locked in position, both in their folded and operative condition. The barrel is secured at its muzzle end to a nose ring on the outer tubular member and is supported by a flanged and co-engaging ring provided upon the inner tubular sliding member when in the extended condition; said latter ring moving forward over a part of the length of the barrel when the firearm is telescoped.

In order that the invention may be more fully understood, reference is made to the accompanying drawings wherein there is illustrated a preferred form of the invention such as is applicable to an automatic firearm and wherein:

Fig. 1 is a longitudinal part sectional elevation of the weapon in its extended and operational condition,

Fig. 2 is a plan of the device shown in Fig. 1,
Fig. 3 is a part sectional elevation of the weapon in its shortened condition and with the butt in its folded condition,

Fig. 4 is a side elevation of Fig. 3, showing the fire selector device in the "safe" position when the telescopic parts are interlocked by the sear,
Fig. 5 is a detail of the folding bayonet locking device,

Fig. 6 is a detail of magazine mouth locking device for the outer and inner tubular members,

Fig. 7 is a top plan view and Fig. 8 is a transverse section, showing additional means of locking the firearm in the extended condition,

Fig. 9 is a detail side elevation, partly in section of the modification illustrated in Fig. 4, with the telescopic members extended, and Fig. 10 is a detail plan view illustrating the modified slot.

Referring to the drawings and to Figs. 1, 2, 3 and 4 the supporting casing of the firearm is formed as two concentric tubular elements, the main tubular element 1 being external to the inner element 2. These tubular elements are adapted on removal of the locking device to slide relatively and telescope axially one within the other. The external tubular part 1 carries the hand grip stock A and trigger and trigger mechanism B, the forward barrel support C, and the bracket clip D fast with the forward end of tubular element 1 for bayonet F. The forward part 35 of the tubular element 1 is perforated as at 3 to provide air cooling of the barrel 4, has a locking key slot 5 with an enlargement 6 towards the end of its rearward length, also the forward barrel support C and bayonet bracket D thereon carry 40

55 and protect the forward sight 7. The rear of the

tubular element 1 is cut obliquely as shown at 8, Fig. 2 and is provided with an axial slot 9 which is aligned with a like slot 9a of the inner tubular element 2, this said axial slot accommodating the bolt cocking handle 10. These slots 9 and 9a in the two tubular elements remain in mutual axial alignment and become coincident at the overlap when the weapon is in its operative condition.

The inner tubular element 2, see Figs. 1 and 3, carries the end cap 11 detachably secured in position in a known manner by a bayonet joint. Said tubular element also carries fixed pivot pins 13, one on either side, upon which are hinged the bifurcated ends of the main lever arms of the folding butt E. The said tubular element 2 also carries at its forward end a supporting collar 14 for barrel breech, and which also limits the axial movement of tube 2. Internally the tubular element 2 constitutes the race for the bolt 16 carrying the firing pin 17 and the recoil spring 18, said spring loading the bolt 16 between abutments formed by the inner face of the cap 11 and the flange 19 formed on the firing pin body 20.

The ammunition magazine socket 21 is of standard type with locking and locating means of a known character. The mouth of the magazine G when the latter is positioned within the coincident slots acts as a locking device keeping the tubular members in relative position in their extended and operative condition, and is further described hereafter. The ejector slot 22 is of conventional and known design positioned adjacent the breech. When, however, the weapon is in a telescoped condition and the magazine removed, both these openings otherwise coincident in the tubes 1 and 2 are closed, thus obscuring these apertures and preventing the admission of dust, dirt or sand.

The trigger mechanism B is similar to that described in application for Letters Patent Serial No. 512,004, filed Nov. 27, 1943, which has now matured into Patent No. 2,432,486, relating to trigger gear for automatic firearms wherein the sear 23 is pivoted on pin 23a between two plates 24 (only the rear one of which is shown), the plate assembly being moved about pin 23a by the trigger 25 when pulled engaging the roller 24a.

Movement of the sear plates 24 is under loading of the spring plunger 26 hinged on pin 27 fast between the plates 24. The tail 23b of sear 23 is slotted and a T-headed sear locking crank lever 28 engages the tail 23b under spring loading of plunger 29. The crank lever 28 is mounted on pivot pin 30, its lower arm 28a engaging or otherwise the firing selector arm 31 fast on pin 31a, said pin protruding externally of the trigger box, see Fig. 4, and being fitted with an outer selector lever 32, capable of being moved in one of three positions, i. e. automatic or continuous fire marked as A, semi-automatic or single round firing marked as R, or non-firing or safe condition marked as S. The cranked lever 28 has a further arm 28b which is grooved to accept the head of selector arm 31 for the safe position (as shown in Figs. 1 and 3) at which position the sear 23 is locked and the weapon inoperative.

The sear 23 in the semi-automatic and "safe" conditions of fire enters the slots 40 and 41 formed respectively in the tubular elements 1 and 2 and which are coincident in the operative condition as shown in Fig. 1, said sear engaging the face of the bolt 16 as shown and arresting its movement. If the firearm is set for single shot firing i. e. R, Fig. 4, and the trigger 25 is pulled, the trigger shoulder engages the roller 24a pivot-

ing the sear plates and assembly, thereby eliminating the sear from the path of travel of the bolt 16, which latter is then free to move under the urge of the spring 18. According to the setting of the fire selection lever 32 the said sear returns to operative position to re-arrest the bolt 16 in single shot firing or is withheld in automatic fire, and in the case of the latter operation the recoil of the cartridge case is communicated to the bolt 16 which compresses the spring 18, the latter returning the bolt and striking pin to act as an abutment and firing device respectively for a succeeding round presented from the mouth of the magazine and fed into the breach 45 of the barrel 4 in the known manner.

A further detent 46 is cut in the bolt 16, with which the sear engages in the telescoped condition, see Fig. 3. When the magazine is removed and the firearm is compacted by telescoping against the loading of the spring 18, the bolt 16 engages the breech face of the barrel 4 and if then the selector lever 32 be set to "safe," the sear which passes through slot 40 in tubular element 1, slot 42 in the tubular element 2, is locked in the bolt detent 46. As previously stated the inner tubular member 2 is provided at its forward extremity with a supporting collar 14, adapted when the firearm is extended to engage upon a thickened part 15 at the breech 45 of the barrel 4. The said collar 14 is flanged at 14a, said flange engaging a corresponding flange 15a formed on the thickened part of the barrel 4. Whilst these flanged parts engage under the loading of the recoil spring 18 the bolt 16 is still in engagement with the face of the barrel breech 45, but the inner tubular element is in its extended and operative condition. If now the cartridge magazine is inserted and the bolt cocking lever 10 be pulled rearward through slots 9 and 9a, the bolt is withdrawn until its front face detent 50 is engaged by the sear 23, when the firearm is potentially ready for operation.

If reference is made to Fig. 6 it will be seen that the outer tubular member 1 is provided with a rectangular mouth 21 into which the ammunition magazine G is positioned and locked in the usual way by catch 49. In the entry of the cartridge magazine feed orifice G1 into the interior of the breech space H, the sides of the magazine G closely engage the magazine opening 2a in the wall of tubular element 2 thereby locking both tubular elements 1 and 2 into a fixed relative position.

Angular motion of tubular element 1 in relation to element 2 while the latter element is in the forward position is prevented by the bolt cocking lever 10 sliding within the axial slot 9 and 9a.

The sliding tubular member 2 carries at its rear the locking cap 11, and the fixed pivot pins 13 upon which the bifurcated ends of the hinged butt E are designed to hinge. This type of folding butt is substantially as described in the specification of my copending application for Letters Patent Serial No. 523,569, filed Feb. 23, 1944 which has now matured into Patent No. 2,424,944. The said butt, however, for the purposes of the present invention has upon its upper member 51 a catch 52 engaging a notch 53 formed in the end cap 11. The cap is capable, under pressure, of axial movement due to a clearance 54 between the locking catch 55 and catch slot 56. The tubular strut member 51 of said folding butt is hinged at its end near the cap to a hinge pin 57a, the strut terminal 58 being shaped to embrace a

shoulder 59 on cap 11. The rear of the strut member 57 is provided with a spring loaded plunger 60 against which is adapted to press the bent over end 61 of a pressed steel butt plate 62, said butt plate 62 is hinged to the strut member 57 by pin 63, the plunger 60 being recessed to allow said pin to cross its path without interference. Said pin 63, however, acts as a limiting stop to movement of the plunger 60. The butt plate hinging on pin 63 is adapted to engage the main butt lever arm, as shown in Fig. 1 by flange 64 engaging the cross piece 51a of the compound sided lever arm 51. Fitted to the butt plate 62 is a headed button 65 mounted upon spring 66, said button 65 being adapted when the butt is folded to enter the hole 6 in slot 5 of outer tubular element 1, see Fig. 2. The said butt is folded pulling back the butt plate 62 and nesting the strut member 57 within the sides of the main lever arms 51. This disengages the strut terminal 58 from the shoulder 59 of the cap 11 allowing said cap 11 to be then pressed in, thereby freeing the catch 52 from the slot 53. The butt plate 62 pivoting on pin 63 and partially urged by plunger 60 folds down on the nested butt members 51 and 57 and the member 57 impinging on the inner head of button 65 compresses the spring 66 causing the button to protrude through the hole in the butt plate 62. The arm 51 is then given arcuate movement about the pivot 13 until the butt in its folded condition comes to rest as shown in Fig. 3, the button 65 entering the hole 6 and then being pushed to the forward end of the slot 5, in which position the butt assembly is securely locked against accidental release.

When the locked telescoped condition of the firearm is released by releasing the sear 23, the spring 18 causes the tube 2 and the folded butt assembly to move rearwards in relation to the tube 1, the button 65 sliding in the slot 5. The firearm is now fully extended and, when locked by the insertion of the magazine, is ready for use with the butt still folded. If, however, the butt is required, the tubular members 1 and 2 are partially telescoped with the magazine removed until the sear, abutting against the rear end of the slot 41 of the tube 2, arrests further movement, at which point the button 65 is in alignment with the enlargement 6 of the slot 5, and by arcuate movement of the butt assembly about the pivots 13, the said button 65 is withdrawn. The tubular members are then allowed to assume their fully extended condition and the butt assembly is free, by further arcuate movement about pivot pin 13, to be hinged rearward until the catch 52 snaps into position of engagement with notch 53. By gripping the knurled faces of the lugs 62a of the butt plate 62 a rearward and downward motion is imparted until the terminal 58 of the strut 57 engages the shoulder 59 on the cap 11, and the turned over extremity 64 of the butt plate 62 contacts the cross piece 51a when a catch 62b by engaging the end of members 51 securely locks the butt assembly in its position for use.

The bayonet F is mounted at the forward end of the tube 1 upon the ear bracket D in a manner similar to that shown in my copending application, Ser. No. 540,693, filed June 16, 1944, the said bayonet being hinged upon a pin 70 supported in said ears and formed with a haft 71, within which is disposed a spring loaded plunger 72 having an external knurled head 73. To place the bayonet in operative position it is hinged outwards and upwards about pivot 70 until the 75

plunger engages the circular perforation 74 aligned as a vent hole in the barrel muzzle support or nose ring C. In this condition it is securely locked and has the shear resistance of the pivot pin 70 and the plunger 72. The bayonet F is displaced for folding by disengaging the plunger 72 from hole 74, hinging the bayonet downward arcuate about its pivot pin 70 and placing same below the outer casing 1 and pressing its grooves 75 into the clip 76 mounted on said tubular element 1 and causing its pointed end to enter the protector sheath 77 adjacent the trigger guard 78, see Fig. 4. The clip 76 locks the bayonet in its folded condition.

Assuming the firearm to have been completely assembled and ready for use with the bolt uncocked and the selector lever at the continuous fire position it is telescoped to shorten its length in the following manner:—

The ammunition magazine G is removed leaving the tubular elements 1 and 2 free to slide one within the other: after the trigger has been pulled to disengage the sear from tube 2 the butt assembly is collapsed and folded forward allowing the button 65 to enter the hole 6 in the key slot 5 in tubular element 1. When the bolt is in engagement with the face of breech 45 i. e. in the uncocked position, the sear 23 is in engagement with the indent 46 of the bolt through the opening 40 of tube 1 and 41 of tube 2. The trigger is depressed to withdraw the sear from opening 41 and by pressure exerted upon the end cap 11 or by holding the cap 11 against the operator's body and drawing by means of the pistol stock the outer tubular member 1 backwards against the loading of the recoil spring 18 the tube 2 is telescoped into tube 1. After movement has started the trigger is released and the sear is riding on the under surface of tube 2, towards the opening 42 in the said tube. When the limit of telescopic movement is reached the openings 40 and 42 and the indent 46 of the bolt become coincident and the sear now engages the indent 46 through the opening 42. The selector lever 32 is now set at "safe" preventing further movement of the sear thereby locking the firearm in the telescoped condition.

The bayonet F is now folded and locked in position as previously described.

To extend the weapon, the selector lever is moved to position A releasing the sear when the recoil spring 18 moves the inner tubular member 2 rearward until the breech ring flange 14a engages the breech flange 15a of the barrel 4. The butt and bayonet can then be unfolded and locked into position by operations respectively as above described, if desired; by insertion of the magazine the tubular members 1 and 2 are then interlocked and the firearm is ready for use after the bolt has been cocked.

If there be great haste to use the firearm the butt and bayonet can remain in a folded condition after the parts 1 and 2 are extended and the magazine inserted.

Again the bayonet clip 76 may be brought nearer the sheath 77 so that the operator with his thumb about the trigger guard 78 can open the clip 76, release the bayonet F and with an upward jerk cause the bayonet to pivot and align itself with the weapon, the plunger 72 automatically entering the aperture 74 in the barrel nose ring C.

It will be observed that when the firearm is in its collapsed condition for transport or parachute delivery to ground troops the side apertures such

as the ejection slot 22 and magazine mouth 21 are closed by the bolt 16 and tube 2.

The firearm made according to this invention is a complete entity without loose parts, or parts that can be unintentionally displaced or lost, and its light weight and compactness are invaluable qualities for arming air borne troops or commandos. Thus taking a firearm of this class having an operative length of 33" with bayonet and butt extended its overall length with folded bayonet is 25½" and 16½" with the butt folded. When the firearm is telescoped and inoperative its length is only 13".

Rigidity of the weapon when operatively extended arises from the fact that there is a mean length of 5¼" of bearing surface between the concentric tubular members, the length lost between the members 1 and 2 alone in the telescopic condition being 3½".

Whilst the above preferred form of the invention has been described in relation to a known type of firearm, there is no limitation thereby implied. Weapons suitable for single shot firing or automatic firing with a "safe" locked position of the sear can equally be made telescopic according to the present invention.

When the magazine G is removed from the socket 21 the tubular elements 1 and 2 are free to telescope. Partial accidental telescoping may occur during change of magazines and, if the spring 18 is in its extended and therefore weakest condition, it may not be strong enough to return the tubes 1 and 2 to the position of coincidence of the magazine socket 21 on the outer tubular element 1, with the magazine opening 2a in the wall of tubular element 2, thereby obstructing entrance of the fresh magazine.

To eliminate this latter possibility a cranked lever 80 (see Fig. 7) may be mounted on a pivot 81 on the forward side of the magazine socket 21. At one end of the lever is a semi-circular catch 82 adapted to enter a convenient ventilating hole 3 of the tubular element 1. At the other end of lever 80 is a thumb-plate 83 by which angular movement can be imparted to the cranked lever against a spring plunger assembly 84 also mounted on the forward side of the magazine socket.

If the firearm is in its telescoped condition the catch 82 bears on the tubular element 2.

If the firearm is extended, as before described, under influence of spring 18, the catch 82 urged by the spring plunger 84 engages the forward end of the tubular element 2, locking the two tubular elements in this condition with the magazine socket 21 and the magazine opening 2a in alignment. When telescoping the firearm the thumb-plate 83 is depressed, thereby disengaging catch 82 from the tubular element 2.

If the firearm is in the extended condition and the folded butt is required, it is necessary to partially telescope the firearm to release it. To overcome such necessity the enlargement 6, see Fig. 1, may be situated at the extreme rear end of the slot 5, as illustrated at 6a in Figs. 9 and 10 so that when the firearm is in the extended condition the button 65 will be in alignment with the enlargement. When the firearm is still extended the butt is held in its folded condition when not required by a catch 85 (Fig. 4) mounted on the outer tubular element 1 engaging a slot 86 formed in the flange 64 of the butt plate 62.

When the butt is required the butt plate is gripped by the ends of the pivot pin 63 and lifted to impart arcuate movement to the butt assembly about pivot 13. Since the catch 85 engaging

the slot 86 restrains the butt plate 62 at the end remote from pivot pin 63, relative angular movement also occurs between the butt plate 62 and the butt members 51 and 57 about pivot pin 63.

5 As the distance between catch 85 and pin 63 increased due to radial motion about pivot 13, the catch is disengaged from the slot 86 allowing the butt to be opened in the manner before described.

The end cap 11 on the inner tubular element 10 2 is secured by a bayonet catch held in position by pressure of the spring 18. To remove the cap it is pressed inwards and rotated and then released. The capability of being pressed is also used to enable the catch 52 of the butt assembly 15 to engage the notch 53, after which the cap is locked by the terminal 58 of the strut 57 engaging the shoulder 59.

When the firearm is extended and the butt is not in use the cap is not locked and if the weapon

20 is uncocked and the spring 18 at its weakest there is a danger of the cap becoming accidentally freed should it be pressed against the body of the user or foul any other obstruction. This is prevented by forming cams or ears 87 (Figs. 2 and 4) on the butt members 51. When the butt is folded these cams or ears are adjacent the inner rim of the cap 11 arresting any inward motion and therefore maintaining the cap in a locked condition. If 25 the butt is unfolded, the cams or ears 87 rotating with the member 51, leave the cap 11 free to move so as to engage catch 52 with notch 53.

I claim:

1. A telescopic firearm comprising a stock section carrying trigger mechanism, a tubular member fixed to the stock section, and a barrel carried by said tubular member and extending longitudinally thereof, a butt section including a tubular member forming a breech block race, and a breech block in said tubular member of the butt section, the tubular member of the butt section being related telescopically to the tubular member fixed to the stock section to enable said sections to be relatively telescoped to shorten the firearm or extended to place the parts thereof in operative position, said trigger mechanism including a sear operative to hold said butt section extended relatively to said stock section.

2. A telescopic firearm comprising a stock section carrying trigger mechanism, a tubular member fixed to the stock section, and a barrel carried by said tubular member and extending longitudinally thereof, a butt section including a tubular member forming a breech block race, a breech block in said tubular member of the butt section, the tubular member of the butt section being related telescopically to the tubular member fixed to the stock section to enable said sections to be relatively telescoped to shorten the firearm or extended to place the parts in operative position, said trigger mechanism including a sear constituting means to hold said butt section in telescoped relation with said stock section.

3. A telescopic firearm comprising a stock section carrying trigger mechanism, a tubular member fixed to the stock section, and a barrel carried by said tubular member and extending longitudinally thereof, a butt section including a tubular member forming a breech block race, a breech block in said tubular member of the butt section, the tubular member of the butt section being related telescopically to the tubular member of the stock section to enable said sections to be relatively telescoped to shorten the firearm or ex-

60 70 75

tended to place the parts in operative position, a recoil spring for closing the breech block and operative to extend the butt section relatively to the stock section, said trigger mechanism including a sear operative to hold the butt section in telescoped relation with the stock section and to release the butt section to permit said spring to extend the butt section and to hold it extended relatively to the stock section.

4. A telescopic firearm comprising a stock section carrying trigger mechanism, a tubular member fixed to the stock section, and a barrel carried by said tubular member and extending longitudinally thereof, a butt section including a tubular member forming a breech block race, a breech block in said tubular member of the butt section, the tubular member of the butt section being related telescopically to the tubular member fixed to the stock section to enable said sections to be relatively telescoped to shorten the firearm or extended to place the parts in operative position, said trigger mechanism including a sear and fire-selection means for setting said sear for single shot firing and for safe condition respectively, and said sear being operative when set for single shot firing condition to releasably hold said butt section extended relatively to said stock section and for releasing the breech block, and operative when set for safe condition to lock said butt section in telescoped relation with said stock section and lock the breech block in closed position.

5. A telescopic firearm comprising a stock section carrying trigger mechanism, a tubular member fixed to the stock section, and a barrel carried by said tubular member and extending longitudinally thereof, a butt section including a tubular member forming a breech block race, a breech block in said tubular member of the butt section, the tubular member of the butt section being related telescopically to the tubular member fixed to the stock section to enable said sections to be relatively telescoped to shorten the firearm or extended to place the parts thereof in operative position, and said tubular members having telescoped portions provided with apertures which register when said butt section and stock section are relatively extended, and an ammunition magazine insertable into said registering apertures and operative to lock said sections in extended relation.

6. A telescopic firearm comprising a stock section carrying trigger mechanism, a tubular member fixed to the stock section, and a barrel carried by said tubular member and extending longitudinally thereof, a butt section including a tubular member forming a breech block race, a breech block in said tubular member of the butt section, the tubular member of the butt section being related telescopically to the tubular member fixed to the stock section to enable said sections to be relatively telescoped to shorten the firearm or extended to place the parts thereof in operative position, said tubular members having telescoped portions provided with apertures which register when said butt section and stock section are relatively extended, an ammunition magazine insertable into said registering apertures, and a detent cooperative with said tubular members to hold them in the relative position in which said apertures register.

7. A telescopic firearm comprising a stock section carrying trigger mechanism, a tubular member fixed to the stock section, and a barrel carried by said tubular member and extending longitudinally thereof, a butt section including a tubu-

lar member forming a breech block race, a breech block in said tubular member of the butt section, the tubular member of the butt section being related telescopically to the tubular member fixed to the stock section to enable said sections to be relatively telescoped to shorten the firearm or extended to place the parts thereof in operative position, a butt pivoted on said tubular member carried by the butt section to fold onto said tubular member fixed to the stock section, and means on the tubular member fixed to the stock section for holding said butt in folded position thereon while said butt section and stock section are in relatively telescoped and extended relations.

15 8. A telescopic firearm comprising stock and butt sections carrying respectively telescopically connected tubular members for lengthening and shortening the firearm, the butt section embodying a butt pivoted on the tubular member carried by the butt section to fold thereon and carrying a headed projection, and the tubular member carried by the stock section being provided with a longitudinal slot having an enlargement therein to receive said projection and permit movement 20 thereof while said sections are relatively telescoped or extended and thereby hold the butt in folded relation with the tubular member carried by the stock section, said projection being disengageable from said slot through said enlargement to permit unfolding of the butt from the tubular member carried by the stock section.

25 9. A telescopic firearm according to claim 8, wherein said enlargement in said slot is located between the ends thereof, and said projection 30 is disengageable from said slot through said enlargement while the tubular members carried by said stock and butt sections are partially telescoped.

35 10. A telescopic firearm according to claim 8, 40 wherein said enlargement is located at the rear end of said slot, and said projection is disengageable from said slot through said enlargement while said butt section is in extended relation with said stock section.

45 11. A telescopic firearm according to claim 8, 45 wherein said enlargement is located at the rear end of said slot, and said projection is disengageable from said slot through said enlargement while said butt section is in extended relation

50 with said stock section, and wherein said butt comprises an element pivoted at one end to said tubular member carried by said butt section, a strut element pivotally connected at one end to the first said element adjacent its pivoted end, 55 and a member pivotally connected to the outer end of said strut element and detachably engageable with the outer end of the first said element whereby the said member is foldable beneath the first-mentioned element when the butt is folded

60 onto said tubular member carried by the stock section and said member carries said projection, and including a catch on said tubular member carried by said stock section engageable with the free end of last said member while said stock and butt sections are relatively extended to retain said butt elements in folded relation with said tubular member carried by said stock section, said element pivotally connected to the outer end of said strut element being releasable

65 70 from said catch by movement of the pivotally connected ends of said elements in a direction away from said tubular member carried by said stock section.

75 12. A firearm comprising a casing having a breechblock mounted therein, a recoil spring for

operating said breechblock, a cap mounted movably on said casing and held in a predetermined position thereon by said spring, a butt pivoted on said casing to swing into an extended position at the rear of the firearm and into a folded position along the length thereof, catch means on said cap and butt operative to lock the butt in extended position and releasable to permit folding of the butt when said cap is displaced from said predetermined position, and means on the butt operative to lock said cap in said predetermined position while the butt is in folded position.

13. A telescopic firearm comprising a stock section, a tubular member fixed to the stock section, a barrel surrounded by said tubular member and supported therein remote from the breech end, a collar on the breech end of the barrel, and a tubular member fixed to the stock section and enclosing the barrel, and a butt section including a second tubular member mounted telescopically within the first-mentioned tubular member for movement relatively thereto into telescoped position to shorten the firearm and into extended position to lengthen the firearm and place the parts thereof in operative position, said second tubular member having a breech block reciprocable therein, and a recoil spring interposed between the breech block and said second tubular member and acting to extend the latter relatively to the first-mentioned tubular member, said second tubular member having a collar on its forward end cooperable with the collar on the barrel to limit the extension of said second tubular member.

14. A telescopic firearm comprising outer and inner telescopic sections, a barrel and trigger mechanism fixed to said outer section, a breech block reciprocable in said inner section, and means associated with said trigger mechanism to latch said telescopic sections in telescoped relation.

15. A telescopic firearm comprising outer and inner telescopic sections, a barrel and trigger mechanism fixed to said outer section, a breech block reciprocable in said inner section, said trigger mechanism including a sear and said breech block having a detent engageable by said sear when the sections are in telescoped relation to latch said sections in said relation.

16. A telescopic firearm as set forth in claim 15 including a fire selection member associated with said sear and movable into a position to lock said sear in engagement with said detent in the breech block.

GEORGE WILLIAM PATCHETT.
